UNITED STATES PATENT OFFICE.

JOHN C. BLACK, OF RICHMOND, CALIFORNIA, ASSIGNOR TO STANDARD OIL COMPANY, OF RICHMOND, CALIFORNIA, A CORPORATION OF CALIFORNIA.

REFINING PETROLEUM.

968,640.

Specification of Letters Patent. Patented Aug. 30, 1910.

Application filed June 13, 1907. Serial No. 378,724.

To all whom it may concern:

Be it known that I, JOHN C. BLACK, a citizen of the United States, residing at Richmond, in the county of Contra Costa 5 and State of California, have invented certain new and useful Improvements in Refining Petroleum, of which improvements the following is a specification.

This invention relates more particularly 10 to the refining of such petroleum as is obtained from wells in the State of California, of which petroleum the burning oil (kerosene) fraction contains an objectionable proportion of (what are herein termed) smoky 15 hydrocarbons, that is to say, hydrocarbons so rich in carbon that they tend to make the oil containing them smoke when such oil is burned in the ordinary petroleum (kerosene) lamps. Moreover, these smoky hydro- 20 carbons are refractory, that is to say, they resist removal by treatment with ordinary sulfuric acid of 66° Baumé (in however large proportion); although they are removable (in large part at least) by means of 25 appropriately stronger acid, as fuming sulfuric acid or sulfuric anhydrid.

The treatment herein above referred to, which belongs to the prior state of the art, 30 consists in agitating the distillate with sulfuric acid (ordinary or fuming or anhydrous, as the case may be) allowing the mixture to settle by standing, drawing off the dark colored liquid (called acid sludge) which settles out and then washing the oil 35 with water and afterward with caustic soda lye. When the treatment is performed with sulfuric acid of suitable strength to attack said smoky hydrocarbons (say, fuming acid containing fifteen per cent. sulfuric anhydrid) the said sludge is very acid 40 (according to my experience), its great acidity being due, as I believe, to the fact that tarry bodies (products of the treatment) surround particles of the acid with a 45 coating which prevents further action by the inclosed acid.

The expression California oil or California petroleum is herein employed as a 50 convenient designation of oil of the foregoing description. It is not confined to oil actually obtained from wells in California; but it includes any petroleum, wherever found or however obtained, the cracked or uncracked burning oil (kerosene) distillate

from which contains the aforesaid refractory smoky hydrocarbons in objectionable proportion and yields a sludge of the character herein above set forth, when treated with sulfuric acid sufficiently stronger than 66° B. acid to remove said smoky hydrocarbons, say fuming sulfuric acid containing fifteen per cent. of sulfuric anhydrid.

In treating California oil, in the form of burning oil (kerosene) distillate either with fuming sulfuric acid or with solid sulfuric anhydrid in order to remove refractory smoky hydrocarbons therefrom, there is a substantial waste of acid (evidenced by the great acidity of the sludge), more acid having to be used than would suffice to combine chemically with the hydrocarbons removed thereby. Moreover, there is also a waste of oil; since such treatment removes (probably in a mechanical way) hydrocarbons which might well be retained in the oil.

I have discovered that the smoky hydrocarbons can be removed from California oil to an industrially useful extent, with comparatively little (if any) waste of acid and oil, by subjecting the California oil in the form of burning oil (kerosene) distillate to sulfuric anhydrid in admixture with a diluent gas (which latter may or may not itself have a beneficial effect on the oil) and in such a state of subdivision and dilution that the mixture remains transparent (or, in other words, nearly or quite free from fog or mist) at twenty degrees Fahrenheit or more below the boiling point of sulfuric anhydrid (115° F.). The explanation, as I believe, for this more efficient reaction of the sulfuric anhydrid on the refractory smoky hydrocarbon is not only that the sulfuric acid is in gaseous condition, but also that practically each molecule is sufficiently separated from every other by intervening molecules of the diluent gas to prevent its coalescing with others and so forming particles of acid (anhydrid) to be enveloped by tarry products. Every molecule of sulfuric anhydrid (or nearly so) consequently combines chemically with one or more molecules of smoky hydrocarbon to form a sulfonic or sulfone compound. Such compounds are heavier than the oil; and settling out they form a sludge which is of a different color and composition from and of less acidity than that which results from treat-

ing the California oil with, say, fuming acid of fifteen per cent. sulfonic anhydrid. I have also discovered that said smoky hydrocarbons can be removed from California oil to an industrially useful extent by sulfuric anhydrid subdivided and in admixture with diluent gas, although the state of subdivision and dilution should not be so great as herein above specified. An even gaseous sulfuric anhydrid can be used effectively without admixture with diluent gas; but the use of undiluted gaseous sulfuric anhydrid would not, according to my experience, have the advantages in avoiding waste of acid and oil in the sludge possessed by the use of sulfuric anhydrid subdivided and in admixture with diluent gas; and my experience also leads to the conclusion that the more perfect its state of subdivision in the diluent gas, in suitably low proportion, the less the waste of acid and oil in the sludge resulting from treating California oil with sulfuric acid of sufficient strength to attack the refractory smoky hydrocarbons thereof. The sulfuric anhydrid would best (I believe) in any case be of catalytic formation and in its original gaseous condition, as contradistinguished from the gaseous product from vaporizing sulfuric anhydrid from the solid state, or from the liquid state, in which it exists, for example, in fuming sulfuric acid; because (for one reason) I believe the freshly catalyzed sulfuric anhydrid to be more active and efficacious than such product; but, irrespective of this, it is (according to my experience) specially advantageous to use the catalytically formed sulfuric anhydrid in its said originally gaseous condition in order to obtain sulfuric anhydrid in the very perfect state of subdivision in which it is obtainable by catalytically converting sulfuric dioxid in a previously constituted mixture of the same with oxygen and diluent gas in proper proportions.

By passing a mixture of sulfur dioxid, oxygen and diluent gas, containing about four volumes per cent. of sulfur dioxid over catalytic material, I have obtained sulfuric anhydrid in admixture with diluent gas in the proportion of about three and a half volumes of the gaseous sulfuric anhydrid to one hundred volumes of the mixture and subdivided therein to such extent that the mixture remained transparent (free from fog or mist) when cooled to 32° F.; whereas, the mixtures which I have prepared of air and sulfuric anhydrid vaporized from fuming sulfuric acid, and then cooled, although containing also three and a half volumes of sulfuric anhydrid per cent. have become full of mist or fog from the condensed sulfuric anhydrid at less than twenty degrees Fahrenheit below the boiling point of sulfuric anhydrid.

It is not inconsistent with good results to have the sulfuric anhydrid in the mixture thereof with diluent gas in a less or a greater proportion than three and a half volumes per cent.; but I have obtained excellent results in refining California petroleum with catalyzed gases containing this proportion of sulfuric anhydrid; and the larger its proportion, the more apt the catalyzed gases are to show fog or mist, when cooled; and in consequence of the less complete state of subdivision and dilution thus evidenced, there is more apt to be an unnecessary loss of acid and oil in the sludge through (as I believe) a coalescing of the molecules of sulfuric anhydrid. Moreover, the larger the proportion of sulfuric anhydrid in the catalyzed gases, the more energetic is the chemical reaction and consequently the greater the danger of unduly raising the temperature of the oil undergoing treatment. On the other hand, an undue increase in the proportion of diluent gas unnecessarily adds to the expense of handling the gases in the treatment and tends to waste oil by evaporation and oxidation (this last, of course, in case the diluent gas should contain oxygen, as it would with air as the diluent).

To obtain a mixture of sulfur dioxid, oxygen and diluent gas suitable for passing over catalytic material, the most convenient mode is to burn sulfur (or sulfur bearing material, as pyrites, for example) in air, as customary in making sulfuric anhydrid, more air being supplied than takes part in the actual combustion. If the air so supplied should furnish just the amount of oxygen needed to convert the sulfur dioxid into sulfuric anhydrid, the content of sulfur dioxid in the mixture so obtained of sulfur dioxid, oxygen and diluent gas could not theoretically exceed about fourteen volumes per cent.; and the catalyzed gases in such case could not theoretically contain more sulfuric anhydrid than about fifteen volumes per cent. It is also possible to make sulfuric anhydrid by catalytic material from sulfur dioxid and oxygen which are free or substantially free (either or both of them) from diluent gas or are mixed therewith in less proportions than results from burning sulfur (or sulfur bearing material) in air and catalyzing the products of such combustion. In fact, sulfuric anhydrid was first successfully manufactured by catalysis by passing sulfur dioxid and oxygen free from diluent gas over the catalytic material. The use of such undiluted or less diluted sulfuric anhydrid is not wholly excluded in practicing the invention, or in part thereof at least.

In subjecting the California oil, in the form of burning oil (kerosene) distillate, to sulfuric anhydrid as aforesaid, the reaction is influenced by the temperature. It is pos-

sible to carry on the treatment at temperatures not so low as twenty degrees Fahrenheit (if any) below the boiling point of sulfuric anhydrid; but it is considered an advantage and special improvement to maintain the oil during the treatment at twenty degrees Fahrenheit or more below said boiling point. And, while this improvement does not necessarily require that the gaseous mixture containing the sulfuric anhydrid should be transparent at the temperature of the oil during its treatment with said mixture, it is considered a further special advantage and improvement to use a mixture which is transparent at such temperature. There need be no practical difficulty in this regard; since a mixture remaining transparent at 32° F. can be prepared as herein above mentioned; and my experience does not tend to show that any benefit (commensurate at least with the extra cost) would result from treating the oil at temperatures below 32° F. I have obtained good results by treating at about 85° F.; but lower temperatures would be more advantageous, there being then, according to my experience, a saving of acid and oil, as compared with an otherwise precisely similar treatment at 85° F. Temperatures between 40° F. and about 60° F. are considered best.

To subject the California oil to the sulfuric anhydrid, use can be made of any known or suitable operations and appliances for bringing gases and liquids into contact with each other. By way of example, an agitator similar to that commonly used in treating oil with sulfuric acid may be specially mentioned, the agitator being made of iron and without the usual lead lining, and the freshly catalyzed gases, composed mainly of diluent gas, being drawn (by suction) or being forced (by pressure) through the distillate and serving to agitate the same; but the distillate can be showered through the freshly catalyzed gases in towers; or other known or suitable arrangements for bringing gases and liquids in contact with each other can be used.

When reference is herein made to the volume per cent. of sulfuric anhydrid in admixture with diluent gas, the sulfuric anhydrid is, of course, to be measured in the gaseous condition; yet non-gaseous sulfuric anhydrid in admixture with diluent gas can be regarded as constituting a specified number of volumes of sulfuric anhydrid per cent. of the mixture, namely, the number of volumes per cent. which the sulfuric anhydrid would occupy if the mixture should be heated sufficiently to vaporize all the non-gaseous sulfuric anhydrid therein.

The California oil in the form of burning oil (kerosene) distillate is treated until it burns properly in a lamp, or at least until it exhibits the desired (and feasible)

amelioration in respect to its content of smoky hydrocarbons. The total amount required of sulfuric anhydrid will, of course, depend more or less upon the special character of oil treated and the extent to which the amelioration thereof is carried; and the rate at which the sulfuric anhydrid is brought into contact with the oil can be varied. Specific instances will be given hereinafter by way of example.

Reference has so far been made only to California oil, as herein above defined; but there are other oils to which the invention, it is believed, can usefully be applied in whole or in part. There are petroleums so far analogous to California oil that they contain in their burning oil (kerosene) fractions in objectionable proportions, objectionable hydrocarbons which resist removal by ordinary concentrated sulfuric acid of 66° B., although removable in large part at least by sulfuric acid of suitably greater strength. Such hydrocarbons may be objectionable either because composed of so much carbon as to be smoky (as in the case of oils obtained from wells in Texas near Beaumont, in Jefferson county) or because composed in part of sulfur (as in the case of oils obtained from wells in Ohio near Lima, in Allen county, and in Indiana). In obtaining burning oil (kerosene) from such an analogous oil, the same in the form of burning oil (kerosene) distillate would be subjected to sulfuric anhydrid substantially as herein above described with reference to California petroleum; only where the refractory hydrocarbons are objectionable on account of their sulfurous character the treatment would be continued until the desired (and feasible) amelioration in respect to such hydrocarbons is shown by known or suitable tests for sulfur.

Moreover, some of the new and original features herein set forth can (usefully I believe in some cases at least) be applied to petroleum in general in the form of burning oil (kerosene) distillate, as well as to California or analogous petroleum as herein above defined in particular, and also to California or analogous petroleum or to petroleum in general in other forms than that of burning oil (kerosene) distillate, and even to non-petroleum oils (mineral, vegetable or animal) susceptible of refinement by means of sulfuric adhydrid. The invention extends to all treatments embodying new and original features herein set forth. The invention also includes new and useful apparatus for use in the refining of California or analogous petroleum or other oil; and each new, useful and original part, improvement or combination (whether of process or apparatus) is intended to be secured for all the uses to which the same can be applied. Modifications by addition, omission or other-

wise are permissible indefinitely so long as the substance is taken of any one or more of the claims at the end of the specification.

Figures 1 and 2 of the accompanying drawings are each of them a diagram of one form of apparatus in accordance with the invention; and the following description gives, by way of example, specific instances of treating California petroleum in the form 10 of burning oil (kerosene) distillate in accordance with the invention, in each of which instances a batch of such petroleum is so treated by the aid of apparatus diagrammatically represented.

Referring to Fig. 1, and assuming that one thousand barrels (forty gallons to the barrel) of distillate, suitable for making water white burning oil (kerosene) of 120° F. fire test, have been obtained from California 20 petroleum in the known or in any suitable way, and are to be treated, such distillate is first given a preliminary treatment by agitation in the ordinary lead lined agitator with ordinary sulfuric acid of 66° B., using, 25 say, about four pounds to the barrel. After settling, and drawing off the sludge, the distillate is charged into the iron agitator *a* provided with an interior perforated fluid distributer *b* at the bottom and an exterior 30 perforated fluid distributer *c* at the top. Gaseous sulfuric anhydrid, subdivided and in admixture with diluent gas, is then passed through the distributer *b* into the distillate in the agitator *a* until test portions of the 35 distillate (removed from time to time for the purpose) show that the desired (and feasible) amelioration of the distillate in respect to smoky hydrocarbons has been effected. Said portions are best prepared for testing by agitation with ordinary sulfuric acid 40 of 66° B. at the rate of about two and a half pounds to the barrel, followed by settling, drawing off the sludge, and washing first with water and then with caustic soda lye; 45 and they can be tested either by burning them in a lamp or by determining their refractive indexes with a refractometer. Removal of smoky hydrocarbons is shown by the refractive index of the distillate being 50 lower after treatment than before the same. To supply the gaseous sulfuric anhydrid in a suitable state of subdivision and dilution, sulfur (or sulfur bearing material) is burned 55 in a sulfur burner *d* by means of air; and the products of such combustion, mingled with air in appropriate quantity to supply the oxygen required to convert the sulfur dioxide into sulfuric anhydrid, are catalyzed, say, by platinum. The combustion in the 60 sulfur burner *d* may be regulated so as to convert each hour about two hundred and twenty five and three-quarters pounds of sulfur (equal to about three and six-tenths ounces of sulfur per hour to each barrel of 65 oil) into sulfur dioxide; and the resulting

products of combustion, consisting of about seven volumes of sulfur dioxide and ninety three volumes (together) of oxygen and diluent gas, (nitrogen), are first subjected in an appropriate purifier *e* to the purifying operations customary in making sulfuric anhydrid by catalytic methods, or to any necessary or suitable purification, and are then passed through the catalyzing chamber *f* containing catalytic material (such as platinum, for example) for converting the sulfur dioxide into sulfuric anhydrid in the known way. From chamber *f*, the catalyzed gases, consisting of about seven volumes of sulfuric anhydrid subdivided and in admixture with about ninety three volumes of diluent gas (composed of nitrogen, oxygen and unconverted sulfur dioxide), are passed through the cooling coil *g* and trap *h* (which receives any products of condensation from coil *g*) 70 and are then introduced through the distributer *b* into the distillate in agitator *a*. At *i* is shown an exhaustor for drawing the gases through the oil. During the treatment the contents of the agitator are kept at a 75 temperature substantially below the boiling point of sulfuric anhydrid, and best between about 40° F. and about 60° F. produced artificially by means of water delivered in jets by distributer *c* onto the outside of the agitator *a*; but if the water supply available is not cold or not copious enough for giving such low temperature, good results are attainable at temperatures above about 60° F. 80 The delivery of the catalyzed gases may be 85 continued a longer or shorter time, according to the amelioration desired; but, with distillate of the character mentioned, a satisfactory burning oil (kerosene) should be obtained after a treatment of about thirty 90 two hours, using altogether about eighteen thousand pounds of sulfuric anhydrid subdivided and in admixture with the diluent gas (composed of nitrogen, oxygen and unconverted sulfur dioxide) in the proportion 95 of seven volumes of the former to ninety three volumes of the diluent gas. The sulfuric anhydrid thus used is at the rate of about eighteen pounds thereof to the barrel 100 of distillate. The time of treatment can be 105 shortened somewhat and the amount of sulfuric anhydrid necessary can be somewhat diminished by using more of the ordinary concentrated sulfuric acid of 66° B. in the preliminary treatment; but the useful maximum would be about ten pounds of the 66° B. acid to the barrel of distillate, according 110 to my experience; inasmuch as said 66° B. acid has been found to have little or no further effect when used in larger proportion. 115 After the treatment with the gaseous sulfuric anhydrid is ended, the distillate is allowed to settle; the sludge is drawn off; and the distillate is transferred to an ordinary 120 lead lined agitator. In this last it is agi- 125 130

tated with about twenty seven hundred pounds of ordinary sulfuric acid of 66° B. (being about two and seven-tenths pounds to the barrel) in order to improve the color and odor, as well as to remove sulfur compounds (whether naturally present or absorbed from the gas and not deposited in the sludge). After drawing off the sludge formed by the 66° B. acid, the oil is washed 10 first with water and then with caustic soda lye and is ready for shipment as burning oil (kerosene).

Referring to Fig. 2, and assuming that one has to treat one thousand barrels of distillate similar to that taken by way of example in the description with reference to Fig. 1, the combustion of sulfur or sulfur bearing material in the sulfur burner *d* by means of air may be regulated as before so 15 as to convert each hour about two hundred and twenty five and three-quarters pounds of sulfur (equal to about three and six-tenths ounces per hour to each barrel of oil) into sulfur dioxide. The products of combustion, containing about seven volumes of sulfur dioxide and ninety three volumes of oxygen and diluent gas, are passed through catalytic material in the form of iron oxide 20 in the chamber *k*. By this material about half the sulfur dioxide is converted into sulfuric anhydrid. The so catalyzed gases are passed through a tower *l*; and their content of sulfuric anhydrid is absorbed in sulfuric acid therein; while at the same time the 25 gases are purified preparatory to the subsequent conversion into sulfuric anhydrid of the sulfur dioxide which escaped conversion by the iron oxide in chamber *k*. From tower *l* the gases are passed through a further purifier *m* and then through the catalyzing chamber *f* containing catalytic material (such as platinum, for example) for converting the sulfur dioxide into sulfuric acid 30 in the known way. From chamber *f*, the catalyzed gases, containing about three and a half volumes of sulfuric anhydrid subdivided and in admixture with ninety six and a half volumes of diluent gas, are passed through the cooling coil *g* and trap *h*, and 35 are then introduced through the distributer *b* into the distillate in agitator *a*. During the treatment the contents of the agitator *a* are kept at a temperature substantially below the boiling point of sulfuric anhydrid, as 40 before described with reference to Fig. 1; and the delivery of the catalyzed gases may be continued a longer or shorter time, as also described with reference thereto. With distillate of the character mentioned, a satisfactory burning oil (kerosene) should be obtained after a treatment of about sixty four 45 hours, using altogether in the agitator *a* about eighteen thousand pounds of sulfuric anhydrid subdivided and in admixture with diluent gas in the proportion of about three

and a half volumes of the former to ninety six and a half volumes of the diluent gas. The sulfuric anhydrid thus used in agitator *a* is at the rate of about eighteen pounds of sulfuric anhydrid to the barrel of distillate. The time of treatment can be shortened somewhat and the amount of sulfuric anhydrid required for a given amelioration of the oil in respect to smoky hydrocarbons therein can be somewhat diminished by using more of the ordinary concentrated sulfuric acid of 66° B. in the preliminary treatment, as before described with reference to Fig. 1. In using in agitator *a* catalyzed gases containing about three and a half volumes per cent of sulfuric anhydrid (as described with reference to Fig. 2) the treatment would best occupy about twice as long as in using therein catalyzed gases containing about seven volumes per cent of sulfuric anhydrid (as described with reference to Fig. 1); but the amount of sulfuric anhydrid consumed in agitator *a* would be about the same. In proceeding as described with reference to Fig. 2, an equal quantity (or thereabout) of sulfuric anhydrid would be absorbed in sulfuric acid in the tower *l* and would be utilized as might be preferred.

The preparation of the catalyzed gases as described with reference to Fig. 1 may be in accordance either with what is known as the single conversion system of making sulfuric anhydrid, of which system the Badische process and the Schroeder process are each an example; while the preparation of such gases as described with reference to Fig. 2 may be in accordance with what is known as the double conversion system of making sulfuric anhydrid, of which system the Mannheim process is an example. The present 105 invention is not restricted to these processes; but any available process of preparing the catalyzed gases can be used.

The gases from the first catalyzing operation of the Mannheim process, namely, the 110 gases from the chamber *k* of Fig. 2, can be used as a form of gaseous sulfuric anhydrid subdivided and in admixture with diluent gas in the proportion of about three and a half volumes per cent; only it is considered 115 uneconomical to do so for one reason on account of the large percentage of unconverted sulfur dioxide in the diluent gas, which unconverted sulfur dioxide must be wasted unless utilized subsequently and the subsequent 120 utilization of which would no doubt be less economical, if not open to difficulty otherwise. The gases from chamber *k* could, for example, be passed into the oil in an agitator through a distributer therein, the same 125 as described with reference to Fig. 2 for the gases from chamber *f* of said Fig. 2.

To apply the gas treatment in making burning oil (kerosene) from petroleum analogous to California oil, as herein above 130

set forth, the procedure can be substantially as described, such analogous oil being subjected in the form of burning oil (kerosene) distillate in agitator *a* to the subdivided and 5 diluted sulfuric anhydrid from the catalyzing chamber *f* until the desired (and feasible) amelioration is effected therein in respect to its content of refractory hydrocarbons (smoky or sulfurous) removable by 10 sulfuric acid stronger than that of 66° B.

For treating California or analogous oil in other forms than that of burning oil (kerosene) distillate, as well as for treating other petroleum in the form of burning 15 oil (kerosene) distillate and in other forms and also for treating non-petroleum oils (whether of mineral, vegetable or animal origin) to which the gas treatment may be applicable, the procedure need not (I believe) be substantially varied. I do not 20 profess to have actually applied the gas treatment to all oils. In any case the gas treatment would be continued until the desired (and feasible) amelioration in the oil 25 under treatment should be effected; and it may well be found expedient to adjust the rate at which the catalyzed gases are delivered into the agitator, according to the case. While sulfuric anhydrid is able to 30 move hydro-carbons which resist sulfuric acid of 66° B., it is also able to remove some at least of the bodies which are removable by 66° B. acid; and hence a gas treatment with sulfuric anhydrid can be used in general 35 wherever a treatment with sulfuric acid is appropriate.

As a general proposition it will (I believe) be found best to apply treatments with ordinary sulfuric acid of 66° B. acid 40 before and after the gas treatment with sulfuric anhydrid; but it may not in all cases be found desirable to do so; and I do not wish to restrict myself to the use of such preliminary and subsequent treatments or 45 of either of them. The proportions of 66° B. acid to be employed in such preliminary and subsequent treatments (if used) would be adjusted according to the case. The oil can be subjected to any other treatment before or after or concomitantly with the gas treatment, if preferred. For example, in 50 refining California oil, the same in the form of burning oil (kerosene) distillate could be given (if preferred) a treatment with fuming sulfuric acid before or after or concomitantly with the gas treatment; and the oil could be rerun before or after the gas treatment.

The expression "other oil as specified" in 55 those of the hereinafter written claims in which it occurs means primarily other petroleum, but by extension it includes non-petroleum hydrocarbon oil which is capable of yielding (or consists in whole or in part 60 of) burning oil distillate, other appropriate

hydrocarbon oil, and also other oil in general, as vegetable fatty oil, for example, to which a treatment with sulfuric acid would be appropriate.

The expressions "means as specified connected with said conveyer for subjecting oil to the thereby conveyed sulfuric anhydrid" and "means as specified connected with said conveyer for subjecting oil to the thereby conveyed gases" are each of them used in 70 contradistinction to means for subjecting a liquid in general to aeriform fluid in general or for subjecting liquid sulfuric acid in particular to aeriform fluid composed of or containing sulfuric anhydrid. Said expressions 75 each of them primarily refer to means composed of (1) an upright vessel for holding a body of the oil during treatment and (2) a distributer near the bottom of said vessel for introducing aeriform fluid composed of or 80 containing sulfuric anhydrid into the body of oil in said vessel, appropriate appliances (not shown) being used to supply the said vessel with California or analogous petroleum or other oil as specified in contradistinction to other liquid, and a distributer for 85 applying cooling liquid to the outside of said vessel being advantageously, but not necessarily, provided. Said expressions, 90 each of them, by extension also include instrumentalities in general of known (or of any suitable) description for bringing aeriform fluid and liquid into contact with each other when, and only when, said instrumentalities are designedly arranged with reference to the subjection of California or analogous petroleum or other oil as specified to 95 aeriform fluid composed of or containing sulfuric anhydrid.

The expression "means as specified for 100 separating the resulting sludge from the so-treated oil" refers primarily to a funnel-shaped bottom on the aforesaid upright vessel in which the oil is held while subjected to the aeriform fluid composed of or containing 105 sulfuric anhydrid, said bottom having a draw off at the small end of the funnel, so that the sludge after settling out in said vessel can readily be drawn off before drawing off the treated oil. By extension said expression includes instrumentalities in general of known or any suitable description for 110 separating liquids of different gravities from each other when, and only when, said instrumentalities are designedly arranged with reference to the separation from California or 115 analogous petroleum or other specified oil of the sludge formed by subjecting the same to aeriform fluid composed of or containing 120 sulfuric anhydrid.

I claim as my invention or discovery:

1. The improvement in refining California or analogous petroleum, consisting in forming outside the oil to be treated a mixture of subdivided sulfuric anhydrid and diluent 130

gas, subjecting such petroleum at sludge producing temperature and in the form of burning oil (kerosene) distillate containing smoky or sulfurous hydrocarbons which resist removal by sulfuric acid of 66° B. to such mixture, continuing the treatment with such mixture until an amelioration of the oil is effected in respect to its content of said smoky or sulfurous hydrocarbons, and separating the resulting sludge and the so refined oil from each other, substantially as described.

2. The improvement in refining California or analogous petroleum, consisting in subjecting such petroleum at sludge producing temperature and in the form of burning oil (kerosene) distillate containing smoky or sulfurous hydrocarbons which resist removal by sulfuric acid of 66° B. to gaseous sulfuric anhydrid, continuing the treatment with such reagent until an amelioration of the oil is effected in respect to its content of said smoky or sulfurous hydrocarbons, and separating the resulting sludge and the so refined oil from each other, substantially as described.

3. The improvement in refining oil, to wit, California or analogous petroleum or other oil as specified, consisting in forming outside the oil to be treated a mixture of subdivided sulfuric anhydrid and diluent gas, subjecting said oil at an artificially produced temperature of not less than twenty degrees Fahrenheit below the boiling point of sulfuric anhydrid to such mixture, continuing the treatment with such mixture until an amelioration is effected in the oil, and separating the resulting sludge from the so refined oil, substantially as described.

4. The improvement in refining oil, to wit, California or analogous petroleum or other oil as specified, consisting in forming outside of the oil to be treated a mixture of subdivided sulfuric anhydrid and diluent gas containing not more than about fifteen per cent. by volume of said sulfuric anhydrid, subjecting said oil at sludge producing temperature to such mixture, continuing the treatment with such mixture until an amelioration is effected in the oil, and separating the resulting sludge from the so refined oil, substantially as described.

5. The improvement in refining oil, to wit, California or analogous petroleum or other oil as specified, consisting in forming outside of the oil to be treated a mixture of subdivided sulfuric anhydrid and diluent gas containing not less than about one per cent. and not more than about fifteen per cent. by volume of said sulfuric anhydrid, subjecting said oil at sludge producing temperature to such mixture, continuing the treatment with such mixture until an amelioration is effected in the oil, and separating

the resulting sludge from the so refined oil, substantially as described.

6. The improvement in refining oil, to wit, California or analogous petroleum or other oil as specified, consisting in forming outside of the oil to be treated a mixture transparent at not less than twenty degrees Fahrenheit below the boiling point of sulfuric anhydrid of subdivided sulfuric anhydrid and diluent gas, subjecting said oil at sludge producing temperature to such mixture, continuing the treatment with such mixture until an amelioration is effected in the oil, and separating the resulting sludge from the so refined oil, substantially as described.

7. The improvement in refining oil, to wit, California or analogous petroleum or other oil as specified, consisting in forming outside of the oil to be treated a mixture transparent at the treating temperature of subdivided sulfuric anhydrid and diluent gas, subjecting said oil at a temperature not less than twenty degrees Fahrenheit below said boiling point to said mixture, continuing the treatment with such mixture until an amelioration is effected in the oil, and separating the resulting sludge and the so refined oil from each other, substantially as described.

8. The improvement in refining oil, to wit, California or analogous petroleum or other oil as specified, consisting in passing a mixture of sulfur dioxide, oxygen and diluent gas over catalytic material for converting sulfur dioxide into sulfuric anhydrid, subjecting said oil at sludge producing temperature to the so obtained catalyzed gases, continuing the treatment with said gases until an amelioration is effected in the oil, and separating the resulting sludge and the so refined oil from each other, substantially as described.

9. The improvement in refining oil, to wit, California or analogous petroleum or other oil as specified, consisting in obtaining a mixture of sulfur dioxide, oxygen and diluent gas by the aid of a combustion of sulfur or sulfur bearing material in air, passing the so obtained mixture over catalytic material for converting sulfur dioxide into sulfuric anhydrid, subjecting said oil at sludge producing temperature to the so obtained catalyzed gases, continuing the treatment with said gases until an amelioration is effected in the oil, and separating the resulting sludge and the so refined oil from each other, substantially as described.

10. The improvement in refining oil, to wit, California or analogous petroleum or other oil as specified, consisting in subjecting the oil at sludge producing temperature to catalytically formed sulfuric anhydrid in its original gaseous state of formation, continuing the treatment with such reagent un-

- til an amelioration is effected in the oil, and separating the resulting sludge and the so refined oil from each other, substantially as described.
11. The improvement in refining oil, to wit, California or analogous petroleum or other oil as specified, consisting in subjecting the oil at a temperature not less than twenty degrees Fahrenheit below the boiling point of sulfuric anhydrid to catalytically formed sulfuric anhydrid in its original gaseous state of formation, continuing the treatment with such reagent until an amelioration is effected in the oil, and separating the resulting sludge and the so refined oil from each other, substantially as described.
12. The improvement in refining oil, to wit, California or analogous petroleum or other oil as specified, consisting in subjecting the oil at a temperature not less than twenty degrees Fahrenheit below the boiling point of sulfuric anhydrid to gaseous sulfuric anhydrid, continuing the treatment with such reagent until an amelioration is effected in the oil, and separating the resulting sludge and the so refined oil from each other, substantially as described.
13. Apparatus for refining oil, to wit, California or analogous petroleum or other oil as specified, consisting of means for catalytically forming sulfuric anhydrid, a gas conveyer leading from said means and conveying thence the therein formed sulfuric anhydrid in its original gaseous state of catalytic formation, means as specified connected with said conveyer for subjecting the oil to thereby conveyed sulfuric anhydrid at sludge producing temperature while said sulfuric anhydrid is yet in its said original gaseous state of catalytic formation, and means as specified for separating the result-
- ing sludge from the so refined oil, substantially as described.
14. Apparatus for refining oil, to wit, California or analogous petroleum or other oil as specified, consisting of means for producing a mixture of sulfur dioxid, oxygen and diluent gas and for passing said mixture over catalytic material for converting sulfur dioxid into sulfuric anhydrid, a gas conveyer leading from said means and conveying thence the gases obtained by passing said mixture over said catalytic material, means as specified connected with said conveyer for subjecting oil to the thereby conveyed gases at sludge producing temperature, and means as specified for separating the resulting sludge from the so refined oil, substantially as described.
15. Apparatus for refining oil, to wit, California or analogous petroleum or other oil as specified, consisting of means for burning sulfur or sulfur bearing material in air and for passing the products of such combustion in the form of a mixture which contains free oxygen over catalytic material for converting sulfur dioxid into sulfuric anhydrid, a gas conveyer leading from said means and conveying thence the gases obtained by passing said mixture over said catalytic material, means as specified connected with said conveyer for subjecting oil to the thereby conveyed gases at sludge producing temperature, and means as specified for separating the resulting sludge from the so refined oil, substantially as described.

In testimony whereof I affix my signature, in presence of two witnesses.

JOHN C. BLACK.

Corrections in Letters Patent No. 968,640.

It is hereby certified that in Letters Patent No. 968,640, granted August 30, 1910, upon the application of John C. Black, of Richmond, California, for an improvement in "Refining Petroleum," errors appear in the printed specification requiring correction as follows: Page 2, line 2, the word "sulfonic" should read *sulfuric*, and same page, line 125, the words "in part" should read *a part*, and that the said Letters Patent should be read with these corrections therein that the same may conform to the record of the case in the Patent Office.

Signed and sealed this 10th day of January, A. D., 1911.

[SEAL.]

C. C. BILLINGS,
Acting Commissioner of Patents.

- til an amelioration is effected in the oil, and separating the resulting sludge and the so refined oil from each other, substantially as described.
11. The improvement in refining oil, to wit, California or analogous petroleum or other oil as specified, consisting in subjecting the oil at a temperature not less than twenty degrees Fahrenheit below the boiling point of sulfuric anhydrid to catalytically formed sulfuric anhydrid in its original gaseous state of formation, continuing the treatment with such reagent until an amelioration is effected in the oil, and separating the resulting sludge and the so refined oil from each other, substantially as described.
